(57) **CLAIM**

I claim the ornamental design for paint brush cleaning device, as shown and described.

DESCRIPTION

FIG. 1. is a perspective view of paint brush cleaning device;

FIG. 2. is a front view thereof;

FIG. 3. is a rear view thereof;

FIG. 4. is a left side view thereof;

FIG. 5. is a right side view thereof; and,

FIG. 6. is a top view thereof.

The broken lines shown in the above-referenced drawings are for illustrative purposes only, illustrating an environment of the invention.
